ABSTRACT

A new cultivar of *Ceanothus* named 'FIT02' that is characterized by chocolate brown and dark purple mature foliage, an upright, vigorous habit, and small clusters of flowers in Summer. In combination these traits set 'FIT02' apart from all other existing varieties of *Ceanothus* known to the inventor.

3 Drawing Sheets

1

Latin name: *Ceanothus griseus var. horizontalis*.

BACKGROUND OF THE INVENTION

The present invention relates to a new and distinct cultivar of *Ceanothus* used as a potted shrub or hedging plant. The new cultivar is known botanically and will be referred to hereinafter by the cultivar name 'FIT02', but may also be known by the Breeder's reference name 'Plum Purple'. In 2001 the inventor discovered a spontaneously occurring, branch sport in a nursery grown batch of *Ceanothus griseus* var. 'Autumnal Blue' (unpatented) in Kilkenny, Republic of Ireland. That year, the inventor propagated the present variety through cuttings of the said branch sport. From a single surviving chocolate brown plant, repeated propagations have built up a population of plants that all exhibited a unique purple evergreen foliage of the type first discovered by the inventor. Thus, the essential characteristic of foliage color was considered by the inventor to have been firmly established.

The selection of FIT02 from the population was based on its overall appearance and growth habit. Thus, although 'Autumnal Blue' may be deemed as the ultimate parent of FIT02, the immediate parent is an unnamed one of many unnamed plants resulting from the extraction, propagation and multiplication of the initial 2001 branch sport discovery.

The distinguishing characteristic of 'FIT02' is its foliage which appears as a combination of chocolate and dark purple, with a vigorous bushy healthy upright growth habit. Otherwise, FIT02 exhibits the same characteristics of Autumnal Blue, including flowers that bloom in Summer as are typical of 'Autumnal Blue' which is the closest comparison plant within the species.

'FIT02' is suitable for use in temperate climates as an ornamental patio plant or contrast plant in a perennial border, and will survive mild winters. 'FIT02' was first asexually propagated by the inventor in Kilkenny, Republic of Ireland in 2001 using vegetative tip cuttings. The distinguishing characteristics of foliage color have been determined to be stable and uniform within the definitions of range described herein.

2

SUMMARY OF THE INVENTION

The following represent the distinguishing characteristics of the new *Ceanothus* cultivar 'FIT02'. In combination these traits set 'FIT02' apart from all other existing varieties of *Ceanothus* known to the inventor. 'FIT02' has not been tested under all possible conditions and phenotypic differences may be observed with variations in environmental, climatic, and cultural conditions, however, without any variance in genotype. 1. *Ceanothus* 'FIT02' exhibits foliage that is chocolate brown and dark purple. 2. *Ceanothus* 'FIT02' is a vigorous bushy evergreen shrub that will eventually spread to 300 cm. in width and 200 cm. in height at maturity. 3. *Ceanothus* 'FIT02' exhibits small clusters of flowers in Summer. 4. 15 *Ceanothus* 'FIT02' is an ornamental shrub used effectively as an accent plant in containers or as a contrast plant in perennial borders. 5. *Ceanothus* 'FIT02' is suitable for temperate climates and will survive mild winters.

BRIEF DESCRIPTION OF THE DRAWINGS

The accompanying color drawings illustrate the overall appearance of the new variety 'FIT02', showing colors as true as it is reasonably possible to obtain in colored reproductions of this type. Colors in the drawing may differ from the color values cited in the detailed botanical description which accurately describe the actual colors of the new variety 'FIT02'.

FIG. 1 is a view of a whole plant four years of age in the landscape showing the plant form and habit;

30 FIG. 2 is a close-up view of the foliage and flowers of the plant of FIG. 1; and

FIG. 3 is a close-up view of the leaves of FIG. 1.

BOTANICAL DESCRIPTION OF THE PLANT

35 The following is a detailed description of the *Ceanothus* cultivar named 'FIT02'. Phenotypic differences may be observed with variations in environmental, climatic, and cultural conditions, without however, any difference in genotype. Color determinations are in accordance with The Royal Horticultural Society Color Chart except where general color terms of ordinary dictionary significance are used. The grow-

ing requirements are similar to the species. The information below is directed to a four year old plant.

-continued

Botanical classification:	<i>Ceanothus 'FIT02'</i>	5	Leaf attachment	Petiolate.
Species:	<i>griseus</i> var. <i>horizontalis</i> .		Petiole diameter	Average length 8 mm
Use:	Ornamental.			Average width 1.5 mm
Commercial classification:	Shrub.		Petiole color	Average height 1 mm
Parentage:	The parent of 'FIT02' is an unnamed plant from a population of plants that resulted from vegetative propagation cycles of the branch sport from <i>Ceanothus griseus</i> var. <i>horizontalis</i> 'Autumnal Blue'.	10	Petiole shape:	Yellow green, Between 152B and 152C
Growth rate:	Vigorous. Grows approximately 15 cm. per month in spring.		Petiole surface:	Flattened oval.
Habit:	Upright.		Stipules.	Pubescent.
Height (at maturity):	200 cm.	15	Leaf margins.	Absent.
Width (at maturity):	300 cm. in width.		Leaf length	Entire to sparsely serrulate, and revolute.
Propagation:	Vegetative tip cuttings.		Leaf width	Finely serrate (approx. 5 teeth per cm)
Root system:	Fine to fibrous.		Leaf color:	Average 4.5 cm
Soil:	Plant in well-drained soils.	20		Average 3.5 cm
Sunlight:	Plant in semi-shade or full sun.		Young, upper side	Dark brown; in between 200A and 202A
Sexuality:	Monoecious.		Mature, upper side	Dark yellow-green 147A but much darker and tinged brownish later fading yellow-green 147A
Growth Cycle	Approximately 12-18 months		Leaf color:	
Branching habit:	Freely branching.	25	Young, under side	Greyed-green 197A; heavily tinged dark yellow-green 147A
Seasonal interest:	Natural flowering season is summer-late summer.		Mature, under side	yellow-green, Between 146A and 147A
Disease resistance and susceptibility:	No more susceptible to pests or disease than similar species.		Foliar fragrance	Absent.
Water Requirements	Low water needs, tolerates drought well	30	Flower:	
High Temperature Tolerance	At least up to 35° c.		Inflorescence	Dense panicle.
Low Temperature Tolerance	At least hardy to USDA Zone 7b		Quantity of inflorescences	Approximately 5-6 panicles per branch.
Stem:			Quantity of flowers per inflorescence	Average: 76
Internode length (lateral stems).	Average is 2.5 cm. between nodes.		Shape of inflorescence	Short and rounded.
Angle at emergence	Lateral branches emerge at an average angle of 45 degree. to 60 degree. to vertical branches.	35	Inflorescence height	Average 5.7 cm
Lateral stem diameter.-	2 mm. in diameter.		Inflorescence width	Average: 3.6 cm
Lateral stem length.	Average stem length of main branches: 90 cm.		Flower shape	Campanulate.
Shape (vertical branches and lateral stems).	Average stem length of lateral branches: 14 cm.	40	Aspect	Facing outward.
Lenticels.	A combination of cylindrical and multicostate.		Flower color:	
Quantity of leaves per lateral branch	Absent.		Color of petal (upper side)	Violet blue, in between 92C and 94D; base lighter, in between 92D and 94D
Lateral color.	Average: 13	35	Color of petal (under side)	Violet blue, in between 92C and 94D; base lighter, in between 92D and 94D
Stem/Branch Color	Upper side greyed-purple Between 183A and 183B		Petals	Five in number.
	Under side yellow-green Between 144B and 144C, and flushed greyed-purple Between 183A and 183B	45	Petal shape	Narrow oblanceolate, concave
	Older stem greyed-purple to brown Between N186C and 200B		Petal apex	Rounded.
Foliation:			Petal base	Attenuate.
Type	Evergreen.	50	Petal margin	Entire.
Leaf arrangement.	Alternate.		Petal surface/texture	Smooth.
Leaf division	Simple.		Petal length	Average: 2.5 mm
Leaf shape	Ovate.		Petal width	Average: 0.75 mm
Leaf base	Obtuse.	60	Unfused or fused	Petals are unfused.
Leaf apex	Acute to obtuse.		Bud color	Violet blue 97A; top darker, between 96C and 96D
Leaf tip	Rounded.		Bud shape	Globular to flattened globular.
Leaf venation	Pinnate.		Bud dimensions	2 mm. in length and 2.25 mm. in diameter.
Vein color (upper side)	Yellow-green 146C		Shape of calyx	Globose when closed and stellate when open.
Vein color (under side)	Yellow-green 146C	65	Dimensions of calyx.	3 mm. in diameter and 2.5 mm. in length.
Leaf surface (adaxial).	Young leaves are pubescent while older leaves are glabrous and glossy.		Number of sepals	Five sepals.
Leaf surface (abaxial)	Young and older leaves are matte and pubescent.		Sepal color (mature, upper side)	Violet-blue, between 92D and 94D; tip darker, between 92C and 94D
			Sepal color (mature, under side)	Violet-blue, between 92D and 94D; tip darker, between 92C and 94D
			Sepal apex	Acute.
			Sepal surfaces (adaxial and abaxial).	Glabrous.
		55	Sepals fused or unfused	Basally fused.
			Sepal base	Truncate.
			Sepal margin	Entire.
			Sepal shape	Ovate.
			Dimensions of sepal	Average 1.5 mm. in width and 2.5 mm. in length.
		60	Blooming period	Average: 1 week
			Quantity of flowers	Approximately 600 flowers per plant.
			Peduncle dimensions	Average 5.3 cm in length and 1 mm in diameter
			Color of peduncle	Yellow-green 145A
		65	Surface of peduncle	Puberulent.

US PP20,754 P3

5

6

-continued

Pedicel dimensions	9 mm. in length and 0.5 mm. in diameter.
Pedicel color	Purple, between 77C and 77D; more violet-blue toward calyx, between 92D and 94D
Pedicel surface	Glabrous.
Fragrance	Slightly sweet.
<u>Reproduction organs:</u>	
Stamens	Five in number.
Form of stamen	Filament.
Dimensions of anther	0.50 mm. in width and 2 mm. in length.
Color of anther	Yellow 11C
Pollen color	Yellow 11D
Pistil	One in number.
Pistil shape	Columnar.
Dimensions of pistil	Average 1 mm. in length
Stigma shape	Trifid. Cleft (3-parted)
Stigma color	Violet-blue 94C
Style color	Violet-blue 94C
Style length	Average: 0.5 mm
Ovary position	Superior.

5	Ovary color	Yellow-green 147A
	Ovary shape	Flattened globular.
	Seed:	
10	Fruit color	Greyed-purple 187A; base is yellow-green 145C
	Fruit surface	Glossy when mature.
	Fruit shape	3-lobed capsule.
	Length of fruit	Average: 4.5 cm
	Fruit texture	Granular and sticky; smooth, glossy.
	Number of seeds	100 per inflorescence.
15	Seed shape	Average 2 seeds per fruit.
	Seed color	Globular.
	Seed dimensions	Dark brown, in between 200A and 202A.
		3 mm. in length and 2 mm. in diameter.

20

I claim:

1. A new and distinct variety of *Ceanothus* plant named 'FIT02' as described and illustrated.
